UNITED STATES PATENT OFFICE.

WILLIAM C. MARTINEAU, OF ALBANY, NEW YORK.

CAR-SEAL.

1,010,439.

Specification of Letters Patent.

Patented Dec. 5, 1911.

Application filed March 9, 1911. Serial No. 613,275.

To all whom it may concern:

Be it known that I, WILLIAM C. MARTINEAU, a citizen of the United States, residing at Albany, Albany county, New York, have invented certain new and useful Improvements in Car-Seals, of which the following is a specification.

My invention relates to seals for the doors of cars, store houses or the like. Its object is to produce a device which shall be simple, efficient, economical in construction, easily sealed, and one which the shackle portion is non-replaceable after unsealing.

Further objects of the invention will appear in this specification and be pointed out in the claims.

In the drawings, Figures 1 and 2 are front elevations of the body or tag portion of the seal in successive stages of construction; Figs. 3 and 4 are side elevations of the body and shackle portions respectively; Fig. 5 is a top plan view of the body as shown in Fig. 2; Fig. 6 is an elevation, partly broken away, of the complete device in operative position; Fig. 7 is a view similar to that of Fig. 2, and Fig. 8 a view similar to that of Fig. 6, showing a modified form of construction.

Referring to the first six figures, 11 designates a blank of sheet metal from which the body portion of my device is made. It comprises a tag portion 12, a head 13, and a series of teeth 14, shown as three in number, integral with and projecting laterally from the head 13. In Fig. 2 the teeth 14 are shown as bent inward upon the head 13, but projecting upwardly therefrom, see Fig. 5. The head 13 is then rolled to form a cylinder, see Fig. 3, with the teeth 14 projecting inwardly at each end thereof. Designating characters, shown in Fig. 6, may then be stamped on the tag portion 12, when the body 11 is hardened and drawn to an approximately spring temper.

The shackle of my device consists essentially of a piece of wire having an enlarged head at each end adapted to be introduced into the head 13 of the body, the teeth 14 spreading resiliently while the enlarged end of the wire is forced therebetween and returning to their normal position to prevent its withdrawal. It is also important to provide means to prevent the introduction of a tubular or other "pick-lock," by which the spring teeth 14 could be retracted to permit the withdrawal of the shackle. In Figs. 4

and 6 I have shown a preferred form of shackle which accomplishes both these results. 21 designates this shackle, which in use is bent into the curved form shown in Fig. 6. At each end it is rolled into a close spiral coil 22 of a diameter permitting it to be forced between the teeth 14 and to be retained thereby within the head 13. At a distance therefrom approximately equal to the length of the teeth 14 is a second coil 23 separated from the end coil 22 by a straight portion 24, the coil 23 being preferably slightly larger in diameter than the coil 22, and so as to close the open end of the head 13 and prevent the introduction of any instrument therein.

The operation of the device will be readily understood from an inspection of the drawings. The shackle 21 is first passed through two staples, one on the car door and the other on the jamb; or through the staple on the frame over which a hasp on the door has already been engaged, when the heads 22 of the shackle are forced laterally into the ends of the body head 13, the spring teeth 14 yielding for this purpose and returning to their normal position as soon as the straight portion 24 comes between them. As already explained, the parts 23 serve to prevent the introduction of any means for tampering with the spring teeth.

In the modified form of the device shown in Figs. 7 and 8, the body portion 31 consists as before of a tag portion 32 and a head 33, having teeth 34 projecting laterally from one only of its sides. Adjacent the other side of the head 32 is stamped a depression 35, which, when the head is rolled to form a cylinder, as shown in Fig. 8, forms an internal bead. Before the rolling operation, one end of a shackle 41 formed with a head 42 is placed in position to be rolled within the head, see Fig. 8, whereby the body and the shackle are permanently secured together. In operation, the free end of the shackle, after being passed through the staple or staples, is forced into the other end of the head 33 and there held by the teeth 34, as before described, the free end of the shackle being, of course, provided with a head of any suitable form to prevent its disengagement.

It will be understood that certain mechanical changes may be made in my device, other than those shown, without departing from my invention. I do not, therefore,

desire to be limited in respect thereto except as set forth in the subjoined claims; it being understood that the word "means" in the phrase "at its other end means for engaging one end of said shackle", in certain of the claims, includes the means shown at the right of both Figs. 6 and 8, as well as any other suitable and desired means to this end.

10. What I claim is:

1. A car seal comprising a body and a shackle; said body consisting of a tag portion and a cylindric head having at one of its ends a plurality of integral, inwardly projecting, spring teeth forming an opening contracted at its inner end, and at its other end means for engaging one end of said shackle; said shackle being provided at its other end with an enlarged head adapted to be forced into the opening at the end of said body head and to be retained therein by the resilient return of said teeth to their normal position, substantially for the purposes set forth.

2. A car seal comprising a body and a shackle; said body consisting of a tag portion and a cylindric head having at one of its ends a plurality of integral, inwardly projecting, spring teeth forming an opening contracted at its inner end, and at its other end means for engaging one end of said shackle; said shackle being provided at its

other end with an enlarged head adapted to be forced into the opening at the end of said body head and to be retained therein by the resilient return of said teeth to their normal position, said shackle being also provided with a second enlarged portion separated from said head and adapted to substantially close the free end of said opening when said shackle head is engaged by said teeth, substantially for the purposes set forth.

3. A car seal comprising a body and a shackle; said body consisting of a tag portion and a cylindric head having at each of its ends a plurality of integral, inwardly projecting, spring teeth forming an opening contracted at its inner end; said shackle being provided at each of its ends with an enlarged head adapted to be forced into one of said openings and to be retained therein by the resilient return of said teeth to their normal position, substantially for the purposes set forth.

4. A car seal shackle consisting of an integral wire having an enlarged coiled end and a second coiled portion spaced from said end by a straight portion of the wire, substantially for the purposes set forth.

WILLIAM C. MARTINEAU.
